CLAIM

The ornamental design for an “ice bucket,” as shown and described.

DESCRIPTION

FIG. 1 is a top, front, and left side perspective view showing one example of our new design for an ice bucket.

FIG. 2 is a front view of the ice bucket shown in FIG. 1.

FIG. 3 is a left side view of the ice bucket shown in FIG. 1, the right side view being a mirror image thereof

FIG. 4 is a rear view of the ice bucket shown in FIG. 1.

FIG. 5 is a top view of the ice bucket shown in FIG. 1.

FIG. 6 is a bottom view of the ice bucket shown in FIG. 1.

FIG. 7 is a top, front, and left side perspective view showing an alternate non-transparent example of our new design for an ice bucket.

FIG. 8 is a top, front, and left side perspective view showing another embodiment of our new design for an ice bucket.

FIG. 9 is a front view of the ice bucket shown in FIG. 8.

FIG. 10 is a left side view of the ice bucket shown in FIG. 8, the right side view being a mirror image thereof.

FIG. 11 is a rear view of the ice bucket shown in FIG. 8.

FIG. 12 is a top view of the ice bucket shown in FIG. 8.

FIG. 13 is a bottom view of the ice bucket shown in FIG. 8; and,

FIG. 14 is a top, front, and left side perspective view showing an alternate non-transparent example of the ice bucket shown in FIG. 8.

The subject matter shown in dashed lines are for illustrative purposes only and form no part of the claimed design.
